ALBERT H. NELLER, OF FAIRFIELD, IOWA, ASSIGNOR TO THE LOUDEN MACHINERY COMPANY, OF FAIRFIELD, IOWA, A CORPORATION OF IOWA.

OVERHEAD TRACK.

1,326,607.

Specification of Letters Patent. Patented Dec. 30, 1919.

Application filed October 16, 1919. Serial No. 331,059.

To all whom it may concern:

Be it known that I, ALBERT H. NELLER, a citizen of the United States, residing at Fairfield, in the county of Jefferson and 5 State of Iowa, have invented a new and useful Improvement in Overhead Tracks, of which the following is a specification.

My invention relates to that class of overhead tracks in which a flexible wire or cable 10 is extended from a building to a distant support out of doors, and is used in connection with a rigid track supported at intervals within the building; and it consists of an improvement in the construction where- 15 by with the same material the trackway may be located either to the right or the left of its supports; the liability of the track wire to crystallize and break at the point of connection will be lessened, and of 20 improvements in other features set forth in the specification specified in the claims.

In the accompanying drawings forming a part of this specification, Figure 1 is a side elevation of an overhead track embodying 25 my invention. Fig. 2 is an enlarged horizontal section on line 2—2 of Fig. 1, looking upward as indicated by the arrow. Fig. 3 is an enlarged horizontal section on line 3—3, of Fig. 1, also looking upward. Fig. 30 4 is a vertical cross section on line 4—4 of Fig. 1, showing the track located on the left side of the support. Fig. 5 is the same showing the track on the right of the support. Fig. 6 is a vertical section on line 6—6 of 35 Fig. 1. Figs. 7, 9, 10, 11 and 12 are views which will be described further on in the specification. Fig. 8 is an enlarged perspective of one of the connecting castings.

Referring to the drawing A represents the 40 ceiling, or other overhead portion of a building. B is one of the timbers above a doorway and C is an outside portion of the adjacent wall. D represents an overhead track located in the building and connected to the 45 ceiling by hangers E, the detailed construction of which will be later described. A vertically disposed supporting member F, preferably of tubular material, is connected to the timber B by clamping members G and 50 H, which are secured to the timber by screws or bolts I.

To the lower end of the member F, castings J and K are secured by means of a bolt L passed therethrough, the upper ends 55 of the castings being adapted to fit the con-

tour of the member. The castings J and K are also adapted to receive the lower and outer end of an inclined brace member M, and are secured thereto by bolts N. This brace member is preferably made of tubular material and its upper end is secured to the ceiling A, or to some other overhead portion of the building. The end of the member may be flattened, as shown in Fig. 1, and may be secured to the ceiling A by 60 bolts O.

The flexible track which, in this instance, is a high carbon steel wire, is represented by P. Its connecting end is bent to form an elongated hook as shown in Fig. 7 which is 65 held in position by clamping castings R and S. These clamp castings are vertically disposed in cross section and form the connection between the rigid track D and the flexible track wire P. They are secured to the 70 castings J and K and the brace member M by bolts N which are passed through all of these parts, as shown by Figs. 2, 4 and 5.

The casting R forms the outside clamp 75 member and the casting S the inside clamp member. These castings are further secured to the brace member M, by the bolt T, as shown in Fig. 2. The inner clamp casting S has a laterally extending lug U which bears against the adjacent side of the brace 80 member, and also against the adjacent end of a laterally extended portion J' on the casting J.

This laterally extended portion J' is adapted to fit in a corresponding recess S' 85 on the central surface of the clamp casting S, said recess being shown in Fig. 12 which is an enlarged transverse section of the clamp casting S between the bolts N. Also, 90 see Figs. 4 and 5.

The track D is preferably C shaped as 95 shown in Fig. 6, and more plainly in Fig. 10, which is an enlarged section of the lower end of Fig. 6, showing the track D and a portion of the track supporting bracket V 100 connected to the lower end of the hanger E by a bolt V'. An extension W adapted to fit the open space in the track D is formed on the inner end of the clamp casting R, and the adjacent end of the track D being 105 slipped over this extension, may be held in connected position by a bolt D', as shown in Fig. 1.

This arrangement makes a very substantial connection between the rigid track D 110

and the flexible track P. The brace M will hold the supporting member F against displacement by the tension of the flexible track or otherwise. The clamp castings R and S being secured to the castings J and K, and to the brace M by three bolts N, N and T, and being braced by the contacting shoulders of the lug U and the extended portion J' of the casting J, and also by the insertion of the extended portion J' in the recess S' of the clamp casting S, will be held firmly in position against a strain in any direction, and especially against the outward horizontal strain caused by the tension of the flexible track.

Provision is also made to prevent the breakage of the track wire from crystallization caused by the repeated bending of the wire at the point of connection with its supporting device. As heretofore made, these supporting devices have always had abrupt or sharply rounded corners against which the wire has had to rest when sustaining a load close to the supporting device. Sometimes this portion of the supporting device has been beveled or made sloping which has helped to some extent but has not entirely overcome the trouble.

The abrupt or sharply rounded corners have remained against which the wire was liable to contact when sustaining a heavy load or when the supporting device became slightly out of adjustment. Sometimes a hinged extension piece located on the upper side of the wire has been used but this arrangement has invariably had an abrupt corner at its termination, which has caused the wire to crystallize and break at that point, as well as at the point of direct connection with the supporting device.

To overcome this trouble I have formed the connecting castings so that the wire cannot come in contact with any abrupt corners either above or below. Fig. 7 is an enlarged side view of the interior of the clamp casting R showing the connecting end of the track wire P located therein. Both of the castings R and S are provided with mating grooves to fit the bent end of the wire, as shown in Fig. 9, which is a transverse section of the casting where one of the bolts N is passed, the bolt being shown broken away.

On each side of these grooves are mating ribs or flanges which I have numbered 13, 14, 15 and 16, and which are adapted to hold the wire in the grooves. The clamp castings are made reversible so that either edge may be turned up. The outer surface of the upper ribs or flanges 13 forms an intermediate trackway between the rigid and flexible tracks D and P. The upper central ribs 14 furnish the bearing support for the track wire P, and are curved downward on an extended radius to the center of

the outer end of the castings R and S, where they meet the ribs 15 bent upward on a similar curve. Fig. 7 shows the outer end of the track wire P slightly deflected downward below the level broken line above it, which on account of the natural sag of the wire is the position it usually assumes when it is not carrying a load, although the outside support may be some higher than the connecting support.

The dotted lines P' are intended to show a loaded carrier wheel pressing the wire down to the maximum extent it will have to go with the heaviest load. It will be seen that even when the wire is pressed down to this extent it is not brought in supporting contact with the abrupt corners or ends of the ribs 14, and that, so far as the wire has been sprung down, it has been supported at all points along the extended curve of the ribs 14, which have prevented a bend short enough to cause crystallization at any point along the deflected portion of the wire.

If under excessive loading, or improper adjustment, it should be found that the curve of the ribs shown in Fig. 7 is not sufficient to prevent the overloaded wire from coming into crystallizing contact with the abrupt end of the ribs 14, and thus causing the wire to break, the curved portion of the ribs may be further extended, which may be readily done by making the clamp castings R and S wider, or by making the lower central ribs 15 straight and extending the curved ends of the ribs 14 down to meet them. In the latter case, the clamp castings would not be reversible and could not be turned upside down as described.

However, if properly adjusted the construction shown in Fig. 7 will be found sufficient to prevent the wire from coming in crystallizing contact with any abrupt corners. It is better in locating the outer support for the flexible track to have it high enough to cause the wire to approach the connecting casting on a level line instead of a little below it, as shown in Fig. 7. This will permit a greater downward deflection before the wire comes in crystallizing contact with the abrupt ends of the supporting ribs 14.

Also, care should be taken to locate the connecting castings so their outer ends will tend to point downward instead of upward, because the tension of the wire has a tendency to draw the support outward and make the outer ends of the castings point upward to a certain extent. A good way to overcome this is to make the castings G and H so that when attached to the beam B they will have a slight inward incline which will cause the member F to stand with its lower end slightly inward, as indicated by the dotted line F'. The member being held in this position by the brace M, will cause the

outer ends of the connecting members R and S to point slightly downward so that the sagging wire would stand even with the dotted line above it, or even a little above this line. This would increase the distance it would have to be deflected before it would come in contact with the abrupt ends of the ribs 14.

The connecting castings R and S being 10 reversible so that either edge can be turned up to form the intermediate trackway, the track may be readily located on either side of the support F and brace M desired. All that is necessary is to reverse the castings 15 J and K on the support F and then by turning the clamp castings R and S upside down the track connection will be located on the opposite side of the support F, the different positions being shown in Figs. 4 and 5. The 20 brace M and hangers E may be adjusted to suit the different positions of the track.

The outer ends of the clamp castings R and S, which form the connecting members, are tapered, as shown to afford an easy approach 25 of the carriage wheels from the flexible track to the connecting members and from there on to the rigid track D. The inner surfaces of the outer ends of the clamping member in contact with the track wire P are rounded 30 out to remove all abrupt corners from actual contact with any part of the track wire.

The bracket V which is attached to the track hanger E by the bolt V' may be adjusted on the hanger by loosening the bolt and 35 sliding it up or down in a slot in the hanger, and then tightening the bolt. The bracket is fitted with a T head X to insert in the opening of the track at one end of a section, and then slide along to the proper point of 40 support and then, to hold it rigidly in position, a wedge shaped key Y is slipped into the opening on the side and is driven under the lower end of the T head X until it is tightened sufficiently to hold the bracket in 45 place.

To facilitate the driving of the key it is provided with a head Z which extends up sufficiently so it can be reached through the opening in the side of the track with a set 50 punch or other means to tighten the key under the T head of the bracket. The construction and arrangement is shown in Fig. 11 which is an enlarged side elevation of a short section of the open side of the track 55 D, the central portion being shown in section. The inserted T head is shown in elevation, and the connecting portion of the bracket V is shown in cross section.

The lower part of the T head is made 60 short so there will be a sufficient space below it to admit the key. It is preferable that the lower end of the head be made narrow to facilitate the driving of the key and that the upper part be made wide, prefer- 65 ably with extended wings, as shown, to rig-

idly support the track. When another style of track is used the extension W will have to be changed to fit it, and the attaching means of the hanger E will also have to be changed to fit the construction of the 70 track.

The features which I claim as new and desire to secure by Letters Patent are as follows:—

1. The combination with a rigid track 75 having supports at intervals, and a flexible track supported at its ends, of a vertically depending member secured at its upper end to an overhead support, castings clamped on the lower end of said member, a brace 80 member having its lower end secured to said castings, and its upper end secured to an overhead support, connecting members secured to said castings and also to the lower end of the brace, and means on said connecting members to attach the adjacent ends of the rigid and flexible tracks in line with each other, and form a continuous track- 85 way for an overhead carriage to run thereon. 90

2. The combination with a rigid track having supports at intervals, and a flexible track supported at its ends, of a vertically depending member secured to an overhead beam by castings clamped on its upper end 95 and secured to the beam, castings clamped on the lower end of said member, a brace member having its lower end secured to said castings, and its upper end secured to an overhead support, connecting members 100 secured to said castings and also to the lower end of the brace, and means on said connecting members to attach the adjacent ends of the rigid and flexible tracks in line 105 with each other, and form a continuous track-way for an overhead carriage to run thereon. 110

3. The combination with a rigid track having supports at intervals, and a flexible track supported at its ends, of a vertically 115 depending member secured at its upper end to an overhead support, castings clamped on the lower end of said member, a brace member having its lower end secured to said castings, and its upper end secured to 120 an overhead support, clamping members, vertically disposed in cross section, secured to said castings and also to the lower end of the brace, the adjacent end of the flexible track being clamped between said members, means to attach the rigid track to said members and the upper edge of said clamp members being adapted to form a continuous trackway between the adjacent ends of 125 said rigid and flexible tracks. 130

4. In combination, a rigid track and a flexible track in line with each other, a depending support having a brace secured to its lower end, and the upper ends of said support and brace being secured to an over-

- head sustaining device, a pair of clamping castings, vertically disposed in cross section, secured to one side of the lower end of said support, means to connect the rigid track 5 to said castings, and means to clamp the adjacent end of the flexible track between the castings, the upper edges of the castings forming an intermediate track-way between the rigid and flexible tracks.
10. 5. In combination, a rigid track and a flexible track in line with each other, a depending support having a brace secured to its lower end, and the upper ends of said support and brace being secured to an over- 15 head sustaining device, a pair of clamping castings, vertically disposed in cross section, secured to one side of the lower end of said support, said castings having mating grooves in their inner faces, means to connect the rigid track to said castings, and the adjacent end of the flexible track inserted in said grooves, and means to clamp and hold the ends of the flexible track in 20 the mating grooves of the castings.
25. 6. In combination, a rigid track and a flexible track in line with each other, a depending support having a brace secured to its lower end, and the upper ends of said support and brace being secured to an over- 30 head sustaining device, a pair of clamping castings, vertically disposed in cross section, secured to one side of the lower end of said support, a pair of parallel mating grooves in the inner faces of said casting, said 35 grooves being curved at their inner ends so as to come together, means to connect the rigid track to said castings, the adjacent end of the flexible track bent to form a hook fitting in said grooves, and means to clamp 40 and hold said bent ends of the flexible track in the grooves of the castings.
7. In combination, a rigid track and a flexible track in line with each other, a depending support having a brace secured to its lower end, and the upper ends of said 45 support and brace being secured to an overhead sustaining device, a pair of clamping castings, vertically disposed in cross section, secured to one side of the lower end of said 50 support, means for connecting the rigid track to said castings, means on the inner faces of said castings for connecting and supporting the adjacent end of the flexible track, said supporting means being down- 55 wardly curved at the outer ends, whereby the downward deflection of said flexible track will be distributed along the curved portion of the support.
60. 8. In combination, a rigid track and a flexible track in line with each other, a depending support having a brace secured to its lower end, and the upper ends of said support and brace being secured to an overhead sustaining device, a pair of clamping 65 castings, vertically disposed in cross section, secured to one side of the lower end of said support, means to connect the rigid track to said castings, flanges on the inner faces of said castings to connect and support the flexible track, the outer ends of said flanges 70 being downwardly curved at their outer ends, whereby the downward deflection of the flexible track under a load will be distributed along the curved portion of said flanges. 75
9. In combination, a rigid track and a flexible track in line with each other, a depending support and a member attached to one side of the lower end of the support for connecting the adjacent ends of the 80 tracks, said member having the portion connecting the flexible track downwardly curved to a point on a radius larger than the width of the member, whereby the downward deflection of said track under a 85 load may be supported at all points along said downward curve, and thus prevent excessive bending of the flexible track.
10. In combination, a rigid track and a flexible track in line with each other, a depending support and a member vertically disposed in cross section, attached to one side of the lower end of said support for connecting the adjacent ends of the tracks, and constituting an intermediate track-way 90 between them, the upper and lower edges on the end connecting the flexible track being curved to a point in the center, whereby either edge of said connecting member may be turned up to form the intermediate track-way, and may be attached to either side of the support without changing the side of contact. 95
11. In a device of the character described, a support having a casting on its lower end 105 with a laterally extended flange, a member to clamp and hold a flexible track having a recess in one of its outer sides adapted to fit over the end of said lateral flange and means to hold the members together. 110
12. In a device of the character described a vertically depending support, a brace for said support, a casting having a laterally extending flange attached to one side of the lower end of said support, a track supporting member with a laterally projecting lug adapted to bear against the lower end of the brace, and be supported against longitudinal displacement by one end of the laterally extending flange, the extending edge 115 of the flange bearing against the adjacent side of the track connecting member, and means to hold the parts together. 120
13. In combination, an overhead track, C shaped in cross section, a hanger for the track having a lateral extension with a T shaped head to enter the opening in the track, and a wedge shaped key to drive below the head and hold it stationary in the track. 125 130

14. In combination, an overhead track, **C** shaped in cross section, a hanger for the track having a lateral extension with a **T** shaped head to enter the opening in the track, and a key having a head extending above the opening in the side of the track to drive under the head and hold it stationary in the track.

15. In combination, an overhead track, **C**,

shaped in cross section, a hanger for the track having a lateral extension with a **T** shaped head made wide on its upper end and narrow on its lower end, to enter the opening in the track, and a key to drive below the head and hold it stationary in the track.

Fairfield, Iowa, October 14, 1919.

ALBERT H. NELLER.
